UNITED STATES PATENT OFFICE

JOHN ZAHIRNIAK, OF WEST, TEXAS

TERRACING MACHINE

Application filed March 18, 1931. Serial No. 523,564.

The present invention relates to an agricultural machine and more particularly to a terracing machine and has for its prime object to provide a machine of this nature capable of being adjusted so that the frame may be disposed in different positions to function properly under varying conditions and also in the provision of a blade which is adjustable with respect to both an upright 10 and a lateral axis.

Another very important object of the invention resides in the provision of a machine of this nature which is exceedingly simple in its construction, inexpensive to manufacture, strong and durable, thoroughly efficient and reliable in use and operation, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:

Figure 1 is a perspective view of the machine embodying the features of my invention.

Figure 2 is a side elevation thereof.

Figure 3 is another perspective view thereof showing the rear wheels differently adjusted.

Figure 4 is a top plan view thereof.

Figure 5 is a perspective view of one of the axle crank shafts, and

Figure 6 is a perspective view of the ring.

Referring to the drawings in detail it will be seen that the letter F denotes generally a frame which includes a pair of spaced parallel side bars 5 connected by a cross bar 6 at their rear ends and having forward portions converging forwardly as is indicated at 7 and on the ends of which is secured a bearing 8. A double tree clevis 9 is fixed to the bearing 8. A rod 10 is slidable and rockable through the bearing 8 and rises from a front wheel truck 11 on the ends of which are journalled front wheels 12. A tongue frame 14 is fixed on the upper end of the rod 10 by

having a pair of spaced ears 15 thereon between which is a block 16. A link 17 is pivotally secured to this block 16 and is adjustably and pivotally secured to a crank 18 on a crank shaft 19 which is journalled in the upper end of a bracket 20 rising from the frame portions 7. A crank 21 extends from the crank shaft 19 and a connecting rod 22 is engaged therewith and extends rearwardly and is pivotally engaged with an intermediate portion of a lever 23 pivoted at one end as at 24 on the rear portion of the frame F and provided with a suitable detent structure 24' cooperable with a notched segment 25 on the frame F.

Obviously by rocking the lever 23 the front end of the frame may be raised and lowered as may be required.

A pair of crank shafts 26 are rockable across the rear portion of the frame in suitable bearings 27 and have inner cranks 28 and outer cranks 29 which terminate in outwardly directed spindles 30 on which are journalled rear wheels 31. Levers 32 are pivotally mounted as at 34 on the frame F and have link connections 36 with the cranks 28 and are formed with suitable detent structures 37 cooperating with notched segments 38. Obviously these levers 32 may be independently adjusted so as to raise and lower the rear end of the frame and to slant the same to either side as may be desired. A seat 39 is suitably mounted on the rear end of the frame so that the three levers 23, 32 and 32 may be accessible for ready manipulation by a person on the seat.

The side bars 5 of the frame are formed of channel irons. Channel iron cross bars 40 are disposed in spaced relation across an intermediate portion of the frame. A ring 41 is rotatable in the channels of the bars 5, 5 and 40, 40. This ring is provided with openings 43 to receive a spring pressed pin 44 extending through an opening in the rear bar 40 and slidable through a suitable bracket 45 thereon so that the ring may be turned to different positions and held in such different positions by the pin engaging in one of the openings 43.

A pair of bars 50 are mounted in upright

positions in the ring 41 being suitably braced as at 51 with respect to the rings and the lower ends of these bars merge into angular extensions 52 in the ends of which is rockable 5 a rod 53 carried on a straight mold board 54 by suitable means 55. Arcuate brackets 56 project from the mold boards and have openings 57 therein so that bolts, pins or the like 58 may be engaged therein and through the 10 extensions 52 to hold the mold board at different angular positions with respect to the extensions 52.

A blade 59 is bolted as at 60 to extend below the bottom edge of the mold board 54. In 15 actual practice it has been found that one of the special features of this machine is that the black land does not stick to the mold board. I have constructed my mold-board perfectly straight and bent the bottom just 20 enough to make the blade which is fastened to the mold board cut the dirt. This terracing machine works somewhat on the order of a grader. The numerous adjustments made possible by the ring and the mold board with 25 respect to its support and the further adjustment made possible by the three levers permit the machine to meet practically all known problems in terracing.

It is thought that the construction, operation, utility and advantages of this invention 30 will now be quite apparent to those skilled in this art without any more detailed description thereof.

The present embodiment of the invention 35 has been disclosed in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit 45 or scope of the invention as hereinafter claimed or sacrificing any of its advantages.

Having thus described my invention, what I claim as new is:

A machine of the class described including 50 a frame formed of channel members, a ring rotatable in the channel members, a ground engaging element, means for mounting the ground engaging element on the ring, means for holding the ring in different adjusted 55 positions, the means for supporting the element comprising a pair of bars fixed in an upright manner in the ring and depending therefrom, a rod extending through the lower ends of the bars, means for fixing the rod on 60 the element, brackets extending from the element and adjustable means engaging the brackets with the bars.

In testimony whereof I affix my signature.
JOHN ZAHIRNIAK.
